UNITED STATES PATENT OFFICE.

JOHN D. PUGH, OF HARRISBURG, PENNSYLVANIA.

HOT-METAL CAR.

1,251,282.

Specification of Letters Patent. Patented Dec. 25, 1917.

Application filed October 13, 1914. Serial No. 866,532.

To all whom it may concern:

Be it known that I, JOHN D. PUGH, a citizen of the United States, and resident of Harrisburg, Dauphin county, State of Pennsylvania, have invented certain new and useful Improvements in Hot-Metal Cars, of which the following is a specification.

This invention relates to hot metal cars for the transportation of molten metal.

10 The objects of the invention are to provide a car which will have the characteristics of simplicity of construction, stability, and which will prevent spilling of the metal and will, also, reduce radiation or the rate of 15 cooling to a minimum.

It is a further object of the invention to provide a car which is adapted to serve as a storage reservoir for metal taken from a blast furnace and intended to be used in a 20 steel making furnace, means being provided whereby the metal may be reheated in case there is a relatively long period of time between the taking of the metal from the blast furnace and its introduction into the steel 25 making furnace.

It is a further object to provide a car having a ladle which can be made in various capacities without changing the lateral or vertical clearances and by using a maximum 30 number of parts which will be standard for different capacities of ladles.

An embodiment of the invention is illustrated in the accompanying drawing in which:

35 Figure 1 is a side elevation;

Fig. 2 is an end elevation with a part shown in section; and

Fig. 3 is a plan view.

Referring to the drawings, 10 and 11 indicate trucks, which may be of any suitable construction and which support a body comprising the ladle supports 12 and 13, which are connected by a frame 14 having a central depressed portion 15. Couplers 16 are attached to the frame 14 in the usual way for the purpose of connecting the car with a locomotive or other device for moving the same.

A ladle preferably in the form of a solid 50 of revolution having a horizontal axis and being symmetrical about a medial vertical plane and comprising a substantially cylindrical middle portion 17 and dished or conical end portions 18 and 19, which are connected to the middle portion, is supported on the members 12 and 13 by means of hori-

zontally spaced trunnions 20 forming parts of the members 21 which are secured to the apexes of the conical portions 18 and 19. The axes of the middle portion 17 of the 60 ladle and of the conical portions 18 and 19 are, therefore, in alinement. The axes of the trunnions 20 are substantially in the horizontal plane of the axis of the middle portion 17, which may be considered the axis of 65 the ladle, and these trunnions are arranged in suitable seats 22 in the supports 12 and 13. Each of the members 21 also carries a trunnion 23, the axis of which is arranged above the axis of the ladle, and in vertical 70 alinement therewith, these trunnions being adapted to receive lifting chains whereby the ladle may be lifted from the car body. On account of the axes of the trunnions 23 being above the axis of the ladle, it will be 75 evident that the center of gravity will be below the axes of these trunnions and therefore the ladle will be in a perfectly stable condition when lifted from the car body.

The ladle is lined with suitable refractory 80 material 24, as is usual, and spouts 25 are arranged on opposite sides of the cylindrical portion 17 above the axis thereof and substantially within the lateral limits of the cylindrical portion as shown in Fig. 2. The 85 openings 26 through the spouts 25 may be closed by means of suitable covers 27, preferably lined with refractory material 28 and having lifting handles 29. The covers 27 are also preferably provided with openings 90 30 through which a gas burner or other heating device may be inserted for the purpose of maintaining the metal, in the ladle, in a fluid condition.

In order to pour the metal from the ladle, 95 without lifting the ladle from the car body, the trunnions 20 are so arranged that the ladle may be tilted to either side of the car about the axis of either pair of the alined trunnions at the opposite ends of the ladle. 10 By having the trunnions 20 substantially on the plane of the axis of the ladle, the latter will be supported in a stable manner and also may be readily tilted. In order to facilitate tilting of the ladle, there are provided 105 on the cylindrical portion 17, preferably below the axis thereof and substantially within the lateral limits of the cylindrical portion, lugs 31 to which a chain may be attached for lifting either side of the ladle. 110 When the ladle has been lifted from the car body and is supported on the trunnions 23,

it may also be tilted for the purpose of pouring the metal therefrom by attaching a lifting chain to either of the lugs 31.

By providing a ladle having a substantially cylindrical middle portion and substantially conical end portions, it will be evident that ladles of different capacities may be constructed by using middle portions of different lengths. The conical end portions and the supporting members 21 may be the same for ladles of different capacities, and furthermore by having the middle portion substantially of the form shown it is not necessary to increase the diameter of this middle portion in order to increase the capacity of the ladle. The lateral and vertical clearances of the car are therefore not changed in making ladles of different sizes, and this is of very great importance because the lateral and vertical clearances are usually limited by the sizes of doors, tunnel openings, etc. The substantially cylindrical middle portion also permits the location of the spouts 25 so that they are substantially within the lateral bounds of the middle portion and at the same time are at such an elevation that practically the full capacity of the ladle may be used without spilling the metal. Thus a ladle is obtained which has a maximum capacity for the track clearances permitted. It is obvious that, if the spouts were located so that they projected outside of the cylinder as seen in plan view, the capacity of the ladle would be correspondingly decreased. The substantially cylindrical and conical portions also provide a ladle of closed construction, the advantages of which are that spilling of the metal is prevented and the radiation of the heat of the metal is reduced to a minimum.

The length of the car body will, of course, be made to correspond with the length of the ladle so that for different capacity ladles it is only necessary to provide car bodies of corresponding lengths, the other parts being standard and may be used with ladles of different capacities.

It will be evident that the construction is not limited to one in which the middle portion of the ladle is truly cylindrical or truly circular in cross section and the ends are straight-sided cones, and I therefore use the terms "cylindrical" and "conical" in their broad sense and intend the claims to cover such modifications of the construction illustrated as come within the spirit and scope of the invention.

Having thus described my invention, what I claim and desire to secure by Letters-Patent is:

1. A hot metal car comprising a suitably supported body and a ladle carried by said body and having a cylindrical middle portion, conical end portions, and a spout on said cylindrical portion.

2. A hot metal car comprising a suitably supported body and a ladle carried by said body and having a cylindrical middle portion, conical end portions, and a spout on said cylindrical portion above the axis thereof.

3. A hot metal car comprising a suitably supported body and a ladle carried by said body and having a cylindrical middle portion, conical end portions, and oppositely arranged spouts on said cylindrical portion above the axis thereof and substantially within the lateral limits of said cylindrical portion.

4. A hot metal car comprising a suitably supported body and a ladle carried by said body and having a cylindrical middle portion, conical end portions, a spout on said cylindrical portion above the axis thereof, and an attachment for a tilting means on the opposite side of said cylindrical portion and below the axis thereof.

5. A hot metal car comprising a suitably supported body and a ladle carried by said body and having a cylindrical middle portion, conical end portions, spouts on opposite sides of said cylindrical portion above the axis thereof, and attachments for a tilting means on opposite sides of the cylindrical portion below the axis thereof.

6. A hot metal car comprising a suitably supported body and a ladle carried by said body and having a cylindrical middle portion, conical end portions, spouts on opposite sides of said cylindrical portion above the axis thereof, and attachments for a tilting means on opposite sides of said cylindrical portion below the axis thereof, said spouts and attachments being substantially within the lateral limits of said cylindrical portion.

7. A hot metal car comprising a suitably supported body and a ladle carried by said body and having a cylindrical middle portion, conical end portions secured to said middle portion and having their axes in alinement with the axis of the middle portion and supporting members secured to the apexes of the said conical portion and each having a pair of horizontally spaced trunnions substantially at the level of the axis of the ladle.

8. A hot metal car comprising a suitably supported body and a ladle carried by said body and having a cylindrical middle portion, conical end portions secured to said middle portion and having their axes in alinement with the axis of the middle portion and supporting members arranged substantially at the apexes of the said conical portions and each having a pair of horizontally spaced trunnions substantially at the level of the axis of the ladle, and a lifting trunnion, the axis of which is in the vertical plane of the axis of the ladle and substantially above the same.

9. A hot metal car comprising a suitably supported body, a ladle carried by said body and having a cylindrical middle portion, conical end portions, a spout on said cylindrical portion, and a cover for said spout having an opening therethrough adapted to receive means for heating the metal in the ladle.
10. A hot metal car comprising a pair of trucks, a body supported on said trucks and having ladle supports arranged above the trucks, and a frame connecting said supports and having a depressed middle portion, and a ladle arranged on said supports and having a substantially cylindrical middle portion, substantially conical end portions, and a spout on said middle portion above the axis thereof.
11. The combination of a ladle comprising a substantially cylindrical portion having ends, the axis of the ladle being horizontal, a spout for the ladle arranged above its axis and substantially within the lateral limits of the cylindrical portion, supporting means secured to the ladle, and a car having seats for said supporting means.
12. The combination of a car, a ladle having closed ends and a substantially cylindrical middle portion, the axis of which is horizontal and extends longitudinally of the car, supporting means on said ends, and a spout on said cylindrical portion above the axis thereof.
13. The combination of a car, a ladle having trunnions by means of which it is supported on said car, said ladle having the lower part of its middle portion of substantially cylindrical form and the upper part of its middle portion closed, and pouring spouts on said middle portion above its axis and substantially within its lateral limits.
14. A hot metal car comprising a suitably supported body, a ladle carried by said body and in the form of a solid of revolution having a horizontal axis, a substantially cylindrical middle portion and dished ends, and being symmetrical about a medial vertical plane and provided with oppositely arranged spouts on said middle portion above said axis and substantially within the lateral limits of said middle portion.

In testimony whereof I affix my signature in presence of two witnesses.
